UNITED STATES PATENT OFFICE.

JINDRICH WALDES, OF NEW YORK, N. Y.

CLASPING DEVICE.

Application filed December 22, 1924. Serial No. 757,332.

My invention relates to claspings devices and more particularly to claspings devices in garters, hose supporters, and the like whereby the stocking or other garment is gripped 5 to hold it in place upon the wearer. These devices generally comprise a depending tab, a stud carried thereby, and a clamping member for clamping the fabric of the stocking or the like upon said stud. Up to the present 10 time, the studs, in most instances, have been constructed as part of a metallic element through which the tab is threaded; such an arrangement presents the disadvantage that it is required to thread the tab through said 15 metal element which takes time and thereby increases the cost of such claspings devices which is further increased by the expense incident to the production of the metal element; the arrangement further is objectionable be- 20 cause the metal element, at least at its edges is exposed to contact with the skin of the wearer and thereby presents the possibility of injury to the fingers and other parts of the person of said wearer. The object of 25 the present invention is to provide a novel device which, in addition to overcoming the above mentioned disadvantages and objections, constitutes a more satisfactory and efficient claspings device. The invention will 30 be fully described hereinafter and the features of novelty will be pointed out in the claim.

In the accompanying drawings, which, without defining the limits of the invention, 35 illustrate an example thereof as applied to garters and other forms of hose supporters, Fig. 1 is a perspective view of a garter with the novel claspings device embodied therein; Fig. 2 is an enlarged front view of the de- 40 vice and the tab by which it is carried; Fig. 3 is a rear view thereof and Fig. 4 is a sectional view on the line 4—4 of Fig. 2.

As shown in the drawings, the garter or 45 hose supporter may be of any conventional form and comprises a band 10 of suitable material, either elastic or non-elastic as desired, which may be made adjustable as to length in the well known way, through the medium of a slide 11 to which one end of 50 the band 10, in such case, is attached and through which said band passes; a connecting member 12 of any suitable type is secured in the looped end of the band 10 in the customary manner. The other end of 55 the band 10 is permanently connected with a pad 13 of suitable dimensions and material

on which an attaching member 14 of any usual form is located for cooperation with the connecting member 12 to detachably fix the garter in place upon the leg of the 60 wearer.

The novel claspings device comprises a stud located upon a carrying member illustrated in the form of a folded tab 15 made of fabric or equivalent material, and de- 65 pending from the pad 13, and a cooperating clamping member 16 connected with the pad 13 by means of a flexible connection 17 so as to depend therefrom in surface parallelism with the tab 15 as shown in Fig. 1. The 70 stud comprises a stem 18 passing through one of the folds of the tab 15 and a disc-shaped base 19 of less diameter than the width of the tab 15, in surface engagement with the rear surface of said tab, it being 75 understood that the stem and base may comprise integral parts of a unit or independent elements properly fastened together and that said stem may be either solid or hollow. A sleeve 20 preferably of rubber is mounted 80 upon the stem 18 in engagement with the front surface of the tab 15 and is fixed in place as the result of the friction of the fabric 15 when the sleeve compresses that fabric against the base 19, as for example 85 by turning over or upsetting the free end of said stem 18 as shown at 21 in Fig. 4. In the preferred form the rubber sleeve 20 is formed with a reduced inner neck *a* 90 and an enlarged outer head *b*, it being understood that in some cases the head may comprise a part of the stem, in which case the sleeve 20 may be of simple, tubular form. In any event, the normal axial length of the sleeve 20 is such as to cause pressure of its 95 under surface against the outer surface of the tab 15 and the upset end 21 of the stem 18 or its equivalent which fixes the device in place upon the tab 15 should be so ar- 100 ranged as to enforce this pressure. This, when a rubber sleeve is used, results in bulging the peripheral surface of the neck *a* out- 105 wardly as shown in Fig. 4 and forces the base or inner end of said neck *a* into engage- 110 ment with the surface of the tab 15 under pressure; the tab is thus securely clamped between the disc-shaped base 19 and the sleeve 20 and a frictional engagement of high degree is developed between the tab 15 and the sleeve 20 which, among other things, prevents the sleeve 20 from rotating upon the stem 18 and also distributes the strains

to which the device is subjected in use, in a manner to reduce to a minimum the tendency of the stud to be torn out of the tab. It will further be apparent from an inspection of Fig. 4 that as the result of the procedure described the peripheral portions of the outwardly and downwardly turned outer edge of the stem 18 embed themselves in the outer part of the material constituting the sleeve, causing physical displacement of such material in an axial direction, thereby resulting in a structure in which the sleeve is firmly held in position between the fabric or carrying member 15 and the turned over head 21 of the stud 18. In the preferred arrangement, the tab 15 is of two-ply formation for instance by being doubled back upon itself, the small-diametered disc-shaped base 19 being located between said plies and being completely covered to prevent said base, i. e. either its flat surface or its edges from coming into contact with the skin of the wearer.

The garter is connected with the stocking 25 in the conventional manner by placing the tab 15 inside thereof and then forcing the clamping member 16 over that part of the stocking which lies over the stud; in this way the stocking is securely connected with 30 the garter which is worn in the usual way by being fastened about the leg through the medium of the connecting member 12 and the attaching member 14.

Because of the fact that the sleeve 20 is 35 under an axial compression and the neck *a* thereof is accordingly bulged outwardly, the clamping member 16 cooperates therewith to develop a clamping action of maximum efficiency upon the stocking whereby the latter 40 is firmly held against any shifting on the stud. The frictional engagement existing between the sleeve 20 and the tab 15, which as previously stated is generally of fabric or equivalent material, is such that the sleeve 45 20 is positively held against rotation on the stem 18 and the latter with its base 19 is fixed against rotation relatively to the tab 15; this arrangement positively serves to prevent the development of, or neutralizes, 50 strains which tend to tear the stud from the tab. The novel clasping device is simple in construction and is easily and quickly attached to the tab or its equivalent and does away with the necessity for any threading 55 of the tab through any element of the device or sewing the tab together to prevent sliding or shifting thereof; the cost of production of the device and of its attachment in operative position is thus materially reduced.

60 Any convenient method may be followed in combining the stud with the tab. For instance, the tab may first be pierced to form a hole through which the stem 18 is inserted. The rubber sleeve 20 is then placed over 65 the stem and the free end of the latter is

upset, by means of a suitable press or its equivalent, to fix the sleeve in position on the stem and to place it under an axial compression as hereinbefore set forth. As previously stated, the base 19 and stem 18 may be made in one piece and in such case may be constructed in any well known manner for instance from flat, sheet stock, it being understood that the stem may be hollow or tubular to facilitate the upsetting of the free end thereof. The stem may be, however, of solid form and the stem and the base may be separable elements, as may also the stem and its upset end. In these latter cases, the stem will obviously be headed or upset against those elements which correspond to the base 19 and/or to the head 21. Furthermore the device may be used in connection with hose supporters of the general class indicated, such as for instance that type which is found in existing corsets, brassières, and the like.

To facilitate the handling and use of the novel device, a plurality of studs, constructed in accordance with the invention, 90 may be mounted, at spaced intervals, upon continuous lengths of tab material and sold in this form, for instance in rolls, to the trade. Such lengths of material, equipped with the studs, could then be cut into predetermined sections for use as required. The shape of the sleeves 20 or the cooperating contour of the clasp 16 may be round, oval, 95 or any desired shape. If the sleeves are oval, for example, two or more stems 18 may 100 be used to secure each such sleeve against one or more base plates. The sleeves 20 may be made of any suitable material including, besides the preferred compressible vulcanized rubber, wood, hard rubber, and other 105 substances.

Various changes in the specific form shown and described may be made within the scope of the claim without departing from the spirit of my invention.

I claim:

A clasping device comprising a carrying member, a stud associated therewith, and a resilient sleeve mounted on said stud and exercising pressure on the carrying member, 115 said stud comprising a hollow stem passing through said carrying member and through the sleeve, a base at one end of said stem contacting with said carrying member, and a head formed by turning the material of 120 said stem outwardly, portions of said outwardly turned material being embedded in the sleeve by physical displacement in an axial direction of part of the material constituting said sleeve, the sleeve being thereby 125 firmly held in position between said head and said carrying member.

In testimony whereof I have hereunto set my hand.

JINDRICH WALDES.
